UNITED STATES PATENT OFFICE.

HARRY MINTZ, OF BOSTON, MASSACHUSETTS.

DESIGN FOR A COUCH OR SIMILAR ARTICLE.

Application filed November 1, 1924. Serial No. 11,259. Term of patent 7 years.

To all whom it may concern:

Be it known that I, HARRY MINTZ, a citizen of the United States of America, residing at Mattapan, Boston, in the county of Suffolk and Commonwealth of Massachusetts, have invented a new, original, and ornamental Design for a Couch or Similar Article, of which the following is a specification, reference being had to the accompanying drawing, forming a part thereof.

In said drawing,

The figure is a perspective view of a couch showing my new design.

I claim:—

The ornamental design for a couch or similar article, substantially as shown.

Signed by me at Boston, in the county of Suffolk and Commonwealth of Massachusetts, this 31st day of October, 1924.

HARRY MINTZ.
